WHISTLE

Philip J. Cormier, Leominster, Mass., assignor to
Robert Y. Grant, Inc., Fitchburg, Mass., a cor-
poration of Massachusetts

Application December 22, 1948, Serial No. 150,418

Term of patent 3½ years

(Cl. D34—15)

To all whom it may concern:

Be it known that Philip J. Cormier, a citizen of the United States, residing at Leominster in the county of Worcester and State of Massachusetts, has invented a new, original, and ornamental Design for Whistle, of which the following is a specification, reference being had to the accompanying drawing, forming part thereof.

Fig. 1 is a side elevational view of a whistle showing my new design;

Fig. 2 is a top plan view; and

Fig. 3 is a front elevational view thereof.

The opposite side is similar to the side shown.

I claim:

The ornamental design for a whistle, as shown and described.

PHILIP J. CORMIER.
